US0D1009124S

(12) **United States Design Patent** (10) Patent No.: **US D1,009,124 S**
 Coster et al. (45) Date of Patent: ** Dec. 26, 2023

(54) **CAMERA**(71) Applicant: **GoPro, Inc.**, San Mateo, CA (US)(72) Inventors: **Daniel J. Coster**, Oakura (NZ); **Heman Au**, San Mateo, CA (US); **Huy Phuong Nguyen**, Alpine, UT (US); **Senka Agic Bergman**, Montara, CA (US)(73) Assignee: **GoPro, Inc.**, San Mateo, CA (US)(***) Term: **15 Years**(21) Appl. No.: **29/897,456**(22) Filed: **Jul. 14, 2023****Related U.S. Application Data**

(60) Continuation of application No. 29/835,920, filed on Apr. 22, 2022, which is a continuation of application No. 29/819,683, filed on Dec. 16, 2021, now Pat. No. Des. 954,128, which is a continuation of application No. 29/786,993, filed on Jun. 3, 2021, now Pat. No. Des. 941,904, which is a continuation of application No. 29/765,003, filed on Jan. 5, 2021, now Pat. No. Des. 921,740, which is a division of application No. 29/694,559, filed on Jun. 11, 2019, now Pat. No. Des. 907,101.
